DISPENSER

Archie H. Gollings, Akron, Ohio

Application October 14, 1936, Serial No. 105,537

8 Claims. (Cl. 221—113)

This invention relates to improvements in a dispenser for dispensing granular or powdered material such as sugar, coffee, malted milk and the like. More particularly it relates to a device which will dispense a predetermined, measured amount of such material.

It is an object of this invention to provide a dispenser adapted to contain a quantity of granular or powdered material and to dispense measured amounts thereof as desired.

Another object is to provide novel means for predetermining, regulating and varying the amount of material to be dispensed, and a further object is to provide novel means to effect the release of material from the dispenser.

Other objects and advantages will become apparent from the following description taken in conjunction with the accompanying drawing.

In the drawing,

Fig. 1 is a vertical section through the device with some parts shown in elevation;

Fig. 2 is a section taken substantially on line 2—2 of Fig. 1;

Fig. 3 is a detail view of the adjustable sleeve;

Fig. 4 is a similar view of one of the telescoping members in respect to which the sleeve is adjustable; and

Fig. 5 is a section taken substantially on line 5—5 of Fig. 1.

In carrying out my invention I provide an upper receiving chamber 10, preferably formed of glass or other transparent material which will permit ready observation of the quantity of material therein. This chamber is frictionally received and held in the upper part of a tapered, funnel-like member 11 which has an elongated, tubular neck 12 terminating in a restricted end portion 13. Member 11 need not be transparent and may be formed of a suitable metal which will polish readily and enhance the appearance of the device. The space defined by chamber 10 and the tapered portion of member 11 will hereinafter be referred to as the upper compartment.

A lower chamber 14, also preferably formed of glass or other transparent material, is frictionally received and held in the upper part of a metallic, funnel-like member 15 having a restricted end portion 16. The upper end of chamber 14 frictionally receives a metallic cover 17 which has an elongated neck 18 arranged to surround neck 12 and extending into engagement with member 11. The space defined by chamber 14, member 15 and the cover portion of member 17 will hereinafter be referred to as the lower compartment.

Intermediate the necks 12 and 18, a tubular sleeve 19 is telescopically arranged with its lower end extending into the lower compartment whereby said sleeve forms a part of the passageway between the compartments. This sleeve is longitudinally adjustable and carries a pin 20 (Fig. 3) which is slidable in an elongated longitudinal slot 21 (Fig. 4) formed in neck 18, said slot having a plurality of small, spaced, bayonet slots 22 leading thereto. Pin 20 is adapted to be received in any of the slots 22 whereby the position of the lower end of sleeve 19 within chamber 14 may be varied to regulate the quantity of material to be received in the lower compartment, as will later be more fully explained.

A rod 23 is mounted for limited longitudinal movement within neck 18 and extends into the lower compartment to a point above the restricted end 16, suitable bearings 24 and 25 for the rod being provided in neck 12 and member 15 respectively. The lower end of rod 23 has secured thereto one end of a cable 26, the opposite end of which carries a ball 27 which serves as a valve to close the opening in the restricted end 16. Adjacent its lower end, rod 23 carries a pin 28 which is engaged by the lower end of a coil spring 29 which surrounds the rod and has its upper end in engagement with bearing 25. The tendency of this spring is to urge the rod downwardly and thus to seat the ball 27.

Intermediate its ends, rod 23 carries a valve 30 which is adapted to have a frictional fit in the restricted end 13 of neck 12, whereby it may be moved into and out of closing position with respect to end 13. Valve 30 may be formed of a suitable rubber composition which will insure proper movement thereof without sticking. The upper end of rod 23 has a ring 31 secured thereto, to which is connected one end of a cable or cord 32. The latter extends through a guide 33, which preferably takes substantially the form of a goose-neck which has one end projecting outwardly of member 11. Guide 33 may be soldered or otherwise secured to member 11, as indicated at 34. A handle 35 is secured on the free end of cable 32 and a stop member 36 is arranged intermediate the ends of the cord. The sizes of the stop member and ring 31 are such that they cannot be pulled into guide 33, and they are arranged to permit limited movement of the cable which in turn will move rod 23 whereby valves 27 and 30 may be moved into and out of closed position.

Chamber 10 may be provided with a suitable cover 37. In order to secure the device to a

suitable support, such as a wall or panel, I utilize a bracket 33 having screw receiving openings 39 and which preferably is secured to members 11 and 15 as shown at 40.

5 In operating my dispenser, before material is placed therein, valve 27 is in closed position and valve 30 is open. Granular or powdered material may then be directed into the top of the upper compartment and this material will flow through 10 the dispenser until it is filled substantially as indicated in Fig. 1. When it is desired to draw out some of the material, cable 32 is pulled whereby valve 30 is closed and valve 27 is opened and all the material below valve 30 will flow out of 15 the device past valve 27. After the material has been dispensed cable 32 is released and spring 29 will immediately pull rod 23 downwardly, thus closing valve 27 and opening valve 30 to permit additional material to pass the latter valve for 20 subsequent dispensing.

Obviously, the granular or powdered material can rise in the lower compartment only as high as the lower end of sleeve 19. Therefore, by adjusting the height of sleeve 19, I am enabled to 25 vary and control the quantity of material dispensed, and at each position of the sleeve a predetermined amount will be available for dispensing.

Although I have described and illustrated the 30 preferred embodiment of my invention, it is to be understood that various modifications thereof may be made without departing from the spirit of the invention or from the scope of the subjoined claims.

35 What is claimed is:

1. In a dispenser, in combination, an upper compartment for initially receiving material to be dispensed, a lower compartment adapted to receive material from the upper compartment, and 40 means for regulating the height of the material in the lower compartment while maintaining the relative positions of said compartments.

2. In a dispenser, in combination, an upper compartment for initially receiving material to 45 be dispensed, a lower compartment adapted to receive material from the upper compartment, a member through which said material passes into said lower compartment, said member extending into said lower compartment a distance sufficient 50 to control the height of said material in said lower compartment, and means for varying the distance said member extends into said lower compartment while maintaining the relative positions of said compartments.

55 3. In a dispenser, in combination, an upper compartment for initially receiving material to be dispensed, a lower compartment adapted to

receive material from the upper compartment, a tubular sleeve extending into said lower compartment and through which said material passes into said lower compartment, and means for varying the height of said sleeve to control the amount of material passing therethrough while maintaining the relative positions of said compartments. 5

4. In a dispenser, in combination, an upper compartment having an elongated neck portion, 10 a lower compartment having an elongated neck portion telescopically arranged with respect to said first-mentioned neck portion, and a member telescopically arranged between said neck portions and extending into said lower compartment. 15

5. In a dispenser, in combination, an upper compartment having an elongated, depending neck portion terminating in a restricted opening, 20 a lower compartment having an upwardly extending neck portion telescopically arranged with respect to said first-mentioned neck portion, a member through which material passes into the lower compartment telescopically arranged between said neck portions and extending into said 25 lower compartment, and a valve operable in said restricted opening to control the passage of material through said member.

6. In a dispenser, in combination, an upper compartment to initially receive material to be 30 dispensed, a lower compartment adapted to receive material from said upper compartment, and a passageway between said compartments, the length of which may be varied to control the 35 quantity of material received in said lower compartment.

7. In a dispenser, in combination, an upper compartment to initially receive material to be dispensed, a lower compartment adapted to receive material from said upper compartment, and 40 connections between said compartments including a sleeve through which material passes into said lower compartment, said sleeve being adjustable to control and vary the quantity of material passing into the lower compartment. 45

8. A dispenser comprising an upper compartment to initially receive material to be dispensed, a lower compartment adapted to receive said material from said upper compartment and having an outlet through which the said material is dispensed, a passageway between said compartments, a valve operable to open and close said passageway, a valve operable to open and close said outlet, means for operating said valves, and means for varying the length of said passage. 55
